CLOCK

Pennie R. Ayres, Roanoke, Va.

Application August 18, 1933. Serial No. 685,776

6 Claims. (Cl. 58—38)

This invention relates to clocks, particularly to chiming mechanism therefor and the objects of the invention are:

To provide a chiming mechanism which shall be simple and cheap to construct, composed of very few parts, and which is readily adaptable to assembly in quantity production without the necessity of delicate hand adjustment of any of the parts.

10 It is also an object to provide a chiming mechanism particularly adapted to synchronous motor electric clocks and to provide a novel control means for taking power from the synchronous motor to drive the chiming mechanism.

15 Further objects and advantages of the invention will be apparent from the following description, reference being had to the accompanying drawings, wherein

20 Fig. 1 is a rear view of a clock movement constructed according to the present invention;

25 Fig. 2 is a top view of the clock;

Fig. 3 is a cross sectional view taken on line 3—3 of Fig. 2;

30 Fig. 4 is a cross sectional view taken on line 4—4 of Fig. 2;

35 Fig. 5 is a fragmentary cross sectional view taken on line 5—5 of Fig. 1;

Fig. 6 is an exploded perspective view showing details of the clock;

40 Fig. 7 is a top view of a portion of the clock mechanism; and

Fig. 8 is a diagram illustrating the layout of certain parts of the mechanism.

45 Fig. 9 is a front view of a clock constructed according to the present invention and on which the dial and hands are not shown for the sake of clearness.

Fig. 10 is a perspective view showing the tripping mechanism.

50 Fig. 11 is a top view partly in section of the power takeoff control mechanism.

Fig. 12 is a cross section through the central hand arbors of the clock.

Fig. 13 is a partial detail view of parts of the 45 invention forming a unitary assembly, the view being taken from the back.

Fig. 14 is a perspective view showing the mechanism attached to the hour wheel.

Fig. 15 is a detail view showing a part of the 50 invention which is attached to the hour wheel of the clock.

Fig. 16 is a perspective view showing the power takeoff control mechanism.

In constructing a chiming mechanism particularly adapted for a synchronous motor electric

clock it is desirable to provide a simple and yet reliable construction. The chiming mechanisms which have so far appeared on the market embodied in synchronous motor electric clocks have been largely patterned after the known types of 5 spring driven chiming mechanisms and include a complete gear train for driving the chiming mechanism. In accordance with the present invention there is provided a chiming mechanism which is driven from the time train of a clock and 10 in which simple but reliable means are provided for controlling the driving of the chiming mechanism from the time train of a synchronous motor clock. In distinction from other clocks in which the chiming mechanism is driven from the 15 synchronous motor through clutches or shiftable gears the present device provides a constantly rotating member driven by the synchronous motor and which is adapted to engage a toothed wheel, and connection between the rotary member 20 and the wheel is established by moving one or more segments of the wheel into and out of the path of the rotary member.

The preferred form of the invention also embraces a novel mechanism for determining the 25 number of strokes at any chiming period, which is considerably simpler and more reliable than the usual count wheel employed for this purpose. There is provided as an integral part of the hammer actuating drum a counting track which is 30 adapted to move through two full revolutions before completing a single cycle of chiming and which has incorporated therewith means for restoring the chime to synchronism with the 35 hands should they ever get out of synchronism.

Referring to Figs. 1 and 2, there is shown a clock movement 2, which is preferably of the usual synchronous motor type such as is used for electric clocks which are provided with chiming mechanisms. The minute arbor 4 of 40 the clock movement carries rigidly therewith behind the front plate 6 a lifting cam 8. The lifting cam 8 has four teeth or projections corresponding to the four quarters of the hour. One of these projections 10 is somewhat longer than the other three, for a purpose later to be described. A lift lever assembly comprising a pivoted shaft 12 having rigidly secured thereto an arm 14 and a two-arm lever 16 is adapted to be actuated by the lift cam 8 through the medium 50 of a pawl 18 pivoted at 20 and spring-pressed by means of the spring 22 against a stop pin 24. The arm 14 lies just to the rear of the front plate 6 and adjacent to the plane of the lift cam 8, while the two-arm lever 16 lies to the rear of 55

the rear plate 26. The two-arm lever 16, shown in perspective in Fig. 6, has an outturned lug 28 located near its hub portion and an oppositely turned lug 30 at about its mid-portion, a flat straight arm 32 at its outermost end and a second outwardly bent arm 34, having a slot 36 in its outwardly bent portion. These parts are preferably formed as an integral member from one piece of sheet metal and may conveniently be formed by die stamping. Extending from the arm 34 is a hooked-shaped stop arm 38 having a portion 40 which is resilient to permit up and down motion of the hook member 38. Pivoted to the lug 28 for free rotation thereon is hub member 42. Slidably mounted in a transverse hole in the hub 42 is a stop slide 44 having a flat downwardly turned hook 46 at its outer end. A spring 48 surrounding the lifting slide 44 urges it to the left in Fig. 6, its motion being limited by a collar 50 secured thereto. A small pin 52 is rigidly secured to the hub 42 at right angles to the slide 44. A spring 54 secured to the rear side of the front plate 6 urges the entire lift lever assembly clockwise in Fig. 1. A spring 56 which is secured to the rear of the rear plate 26 projects under and to the right of the pin 52, but normally lies out of contact therewith. When the lift lever assembly rotates counterclockwise from the position shown in Fig. 1 the lug 30 engages the spring 56, causing it to press against the pin 52 and urge hub 42 and with it slide 44 to rotate in a counterclockwise direction when viewed from the top.

An auxiliary front plate 58 and an auxiliary rear plate 60 are secured to the front and rear main plates 2 and 26, respectively, by pillars 62 and screws 64 together with an auxiliary support arm 66 secured to the rear plate 26. A shaft 68 is pivoted in suitable bearing holes in the plates 58 and 60 and carries rigidly secured thereto a unitary drum assembly which constitutes the main operating mechanism of the chiming attachment. This drum assembly comprises a toothed wheel 70 having provision for twenty-five teeth, but having three mutilated portions 72 equivalent to the space occupied by two teeth each, as best shown in Fig. 4. Located on the rear side of the toothed wheel 70 are three light sector pieces 74 which are loosely located with respect to the toothed wheel 70 by pairs of pins 76, 77 projecting into elongated holes 78 in toothed wheel 70. On the opposite side of the wheel 70 are three raised track portions 80 corresponding to the spaces between the segments 74 and each having a rounded off end portion 82, as shown in Fig. 4. A wheel 86 carrying a series of projecting pins 88 is secured to a shaft 85 in the main clock movement and is geared to rotate with the wheels of the motor at such a speed that one of the pins 88 will pass a given point in the interval desired between individual adjacent strokes of the chiming mechanism. The pins 88 lie in the path of the teeth of the wheel 70 and also the teeth of the sector members 74 and as each pin 88 passes the wheel 70, it will step the same around a distance corresponding to one tooth. The sector members 74 are resiliently retained against the wheel 70 by leaf springs 90 secured to a ring 92 which in turn is secured to the hub 94 of the wheel 70 by a snap ring 96, as shown in Fig. 5.

The remainder of the drum assembly secured to shaft 68 comprises a series of hammer operating toothed wheels 98 having their respective teeth so placed as to operate the hammers

through a full cycle of chimes in two full revolutions of the drum assembly, as is well known in chiming devices for striking the Westminster chime. A counting track is formed preferably as an integral portion of the toothed wheels 98 and preferably comprises a series of three tracks, 100, 102, 104, the layout of these tracks being illustrated diagrammatically in Fig. 8 to be described hereinafter. The toothed wheels 98 in their rotation are adapted to depress the tails 106 of the hammer levers 108 by means of the pins 110, in the well known manner. The hammer levers 108 normally rest on the resilient striking piece 112 secured by means of a bar 114 to the plates 58 and 60. Chime bars 116 are mounted in a support 120 of suitable construction and are located immediately beneath the normal rest position of the hammers, as is well known in the art. An hour lift cam 122 is formed integral with the forward edge of the track 100 for initiating operation of an hour striking mechanism of suitable form and is adapted to raise a pin 124 mounted in the end of a lever 126 pivoted to the rear plate 26 at 128 and having a nose 130 adapted to engage behind the heel 132 of an hour strike lift lever 134, forming part of the hour striking mechanism which may be of any well known type, but is preferably of the type shown in my copending application Serial No. 661,350, filed March 17, 1933, entitled Clock, and preferably driven by shaft 65.

The hour strike lift lever 134 carries a pin 136 adjacent to its heel 132 adapted to be engaged by the arm 32 of two-arm lever 16. Secured to the forward auxiliary plate 58 by screws 138 is a bracket 140. A vertical shaft 142 is pivoted in the bracket 140 and carries at its upper end a hub 144 rigidly secured thereto. Loosely pivoted to the hub 144 and projecting through an elongated slot 146 therein is a rigidly projecting control arm 148. The control arm 148 is urged in a clockwise direction relative to the hub 144 by a spring 147. At the mid-portion of the shaft 142 there is rigidly secured thereto a stop arm 150 which is adapted to ride on the tracks 80 and on the toothed wheel 70 in the space between the ends of the track. Each of the pins 77 is somewhat longer than the thickness of the toothed wheel 70 and normally projects from the front side of the toothed wheel 70 in the space between the ends of the tracks 80 and in the path of movement of the arm 150 at certain positions of the toothed wheel 70. The stop slide 44 carries an upstanding pin 152 for coaction with the control lever 148, while the flat nose 46 of the slide 44 is adapted to ride in the tracks 100, 102 and 104. These tracks are laid out as shown in Fig. 8 wherein there is represented diagrammatically a development of the tracks for two revolutions of the drum assembly, the two halves of this figure being duplicates of the tracks as they are constructed.

The Westminster chime is made up of forty chime strokes and ten dead beats in its full cycle for chiming all four quarters of the hour. The first-quarter chime requires four chime strokes and one dead beat, or, since two revolutions of the drum produce fifty strokes and dead beats altogether, one-fifth of a revolution. The half-hour chime requires eight chime strokes and two dead beats, or two-fifths of a revolution. The three-quarter hour chime requires twelve chime strokes and three dead beats, or three-fifths of a revolution, and carries over into the first fifth of the second revolution. The hour

strike requires sixteen chime strokes and four dead beats and the remaining four-fifths of the second revolution.

The track 100 has at its beginning a stop bar 154 adapted to engage the nose 46 and the slide 44. Proceeding to the right in Fig. 8 the track 100 next has a diagonal throwover portion 156 for shifting the nose 46 over into track 102. One-fifth of a revolution from stop 154 is a stop 158 in track 102. Two-fifths of a revolution further on there is another stop 160 in track 102 and in the last fifth of a revolution there is a diagonal throwover member 162 for throwing nose 46 into track 104. In the track 104 at the ends of the first fifth of a rotation is another stop member 164 which is higher than the other stops 154, 158 and 160. The series of filled and open circles in Fig. 8 represent diagrammatically the path of the nose 46 along the tracks 100, 102 and 104 for a full chime cycle, the filled circles representing chime strokes and the open circles representing dead beats.

In operation, between chiming periods the segment 74, which happens to be adjacent to the pins 88, is pressed out of their path by the lever 150 due to the fact that on the last (dead beat) step of the drum assembly one of the stop members 154, for example, pulls the nose 46 and the stop slide 44 to the right into the position shown in Fig. 1, this movement moving stop lever 148, hub 144, shaft 142 and stop lever 150 counterclockwise when viewed in Fig. 2. As the minute hand approaches the indication of fifteen minutes past the hour, lift cam 8 through one of its shorter projections depresses the left-hand end of arm 14 through pawl 18 and thus turns the lift lever assembly 16, 44 counterclockwise in Fig. 1. This in turn lifts the nose 46 of the slide 44 up out of engagement with the stop 154 in track 100, whereupon spring 48 moves slide 44 quickly to the left in Fig. 1, so that the nose 46 lies to the left of stop 154. The counterclockwise rotation of the lift lever assembly also 45 raises the hook member 38 up into engagement with the left-hand edge of control lever 148, so that, although the pin 152 on slide 144 is retracted from control lever 148, the latter cannot move because it is now blocked by the hook member 38. As the minute hand reaches the designation of fifteen minutes after the hour, lifting cam 8 passes beyond the pawl 18, thus permitting the lift assembly to rotate clockwise under the urge of spring 54. This movement 50 drops hook member 38 down out of the path of control lever 148. The leaf spring 98 on the rear of wheel 70 now urges segment 74 forward against the toothed wheel 70, which movement rotates stop lever 150 through pin 71, and through shaft 142 rotates control lever 148 clockwise when viewed in Fig. 2.

Upon movement of sector 74 into engagement with wheel 70 the teeth on sector 74 lie in the path of the pins 88 which are constantly rotated by the clock motor and thus rotate the wheel 70 and sectors 74 in a clockwise direction step by step in Fig. 1. There being twenty-five teeth on the wheel 70 and the three sectors 74 altogether and there being required twenty-five chime strokes and dead beats for one revolution of the drum assembly, it will be seen that for each step of rotation of the drum assembly one chime stroke or one dead beat, as the case may be, will take place. At the first-quarter there will be four chime strokes and

one dead beat, the toothed wheels 98 operating the hammers 100 in proper sequence. After the first stroke the rounded off end 82 of the raised track 80 will come under the lever 150 and hold it in the position to which it was pushed by the spring 98 through the pin 71. During the middle portion of the striking period, the nose 46 engages the throwover portion 156 which throws it into track 102 and in the latter portion of the chiming period the stop member 158 in track 102 will engage the nose 46 and pull the slide 44 to the right in Fig. 1 against the spring 48. Due to this movement of slide 44 pin 152 will move control lever 148 counterclockwise, but since stop lever 150 still rides on the track 80 hub 144 and shaft 142 will not partake of this movement, slot 146 and spring 147 permitting this movement of control lever 148 relative to hub 144 at the end of the last step of the chiming period. As wheel 70 is rotated sufficiently so that the end of track 80 passes from under lever 150, the latter immediately under the urge of spring 147 moves inwardly toward wheel 70 and through pin 71 pushes the next segment 74 out of the path of pins 88. It will be apparent that spring 98 is weaker than spring 147 to permit this movement. As soon as sector 74 moves out of the path of pins 88, the drum assembly remains at rest for the next quarter of an hour, during which lift cam 8 gradually moves the lift assembly, in the manner previously described, to release it at the half hour. The chiming actions which take place at the half hour and three-quarter hour are similar to that taking place at the quarter hour with the exception that nose 46 rides in different portions of the tracks 100, 102 and 104, as clearly illustrated in Fig. 8, and that the number and sequence of strokes are, of course, different. At the hour the long projection 10 of the lift cam 8 engages the pawl 18 and thus lifts the lift lever assembly higher than at the other chiming periods. Stop 164 in track 104 is higher than the other stops and nose 46 is raised sufficiently high to clear it, as well as to clear 45 dividing walls between the tracks. Since on the high lift at the hour, lug 30 engages spring 58, there will be an urge exerted on the hub 42 through pin 52 to rotate counterclockwise in Fig. 2 and thus the nose 46 moves over into 50 position above the track 100. Should the chiming mechanism get out of synchronism with the hands of the clock, the nose 46 will come to stop 164 at some time before the hour indication by the hands. The chime will then fail to operate 55 at successive quarter hours until the hands come to the hour position because the short projections on the lifting cam 8 do not raise the lift lever assembly sufficiently high for nose 46 to clear stop 164. When the hands again indicate 60 the hour, however, nose 46 will be raised by the long projection 10 on lift cam 8 sufficiently high to clear stop 164, whereupon the hour is chimed and the chiming mechanism is again in synchronism with the hands. On the high lift 65 at the hour, arm 32 engages pin 136 to raise the lift lever 134 to its full stroke, whereupon the nose 130 moves up to position behind the heel 132 due to the weight of the other end of lever 126. At the end of any hour chime period the hour 70 lift cam 122 raises pin 124 and thus removes the nose 130 from the heel 132 of the lift lever 134 for the hour striking mechanism. This permits the lever 134 to fall and start the hour striking mechanism, in a manner later to be described. 75

The hour striking mechanism described in my copending application previously referred to is a unitary attachment to the front face of the clock movement and is illustrated in Figs. 9 to 5 inclusive. A bridge member 170 is secured to the front of the plate 2 in spaced relation by means of suitable fastenings 172 and carries fixed thereto a sleeve 174. Mounted on the sleeve 174 for free rotation thereon is a toothed wheel 176. Pivoted on the plate 170 at 178 is a control lever 180 having a hole 182 formed therein for permitting limited oscillation about the pivot 178. The toothed wheel 176 is mounted on the sleeve 174 by means of a hub member 184 having a flange 186 at its rear end which is spaced from the wheel 176. Between the flange 186 and the wheel 176 a spiral spring 188 is located having its inner end fastened to the hub 184 and its outer end secured to a post 190 mounted in the plate 170. The wheel 176 and its hub 184 are secured on the sleeve 174 by suitable fastening means such as the ring 192 pressed on the back end of the sleeve 174. Similar means are provided such as the ring 194 for securing the wheel 176 to the hub 184. A spring member 196 is fastened to a post 198 secured to the plate 170 and has its opposite end bearing against the lever 180 to bias its top end to the right in Fig. 9. The plate 170, sleeve 174, wheel 176, control lever 180 and the associated parts just described are adapted to be assembled together as a unit for ready attachment to the remainder of the clock mechanism. The time train of the clock includes the usual dial gears 200, 202, 204 and 206, the latter of which is the hour wheel and is provided with two diametrically opposed longitudinal slots 208. On the front face of the hour wheel 206 there is attached by means of suitable rivets 210 extending into the slots 208 a sliding stop member 212 carrying a boss 214 thereon projecting to the front of the plane of the stop slide 212. One end of the slide has a rounded nose 216 adapted to cooperate with a fixed cam 218 secured to the main frame plate 6 for the purpose of camming the stop slide 212 to the left in Fig. 15 during a certain portion of the rotation of wheel 206. A spring 220 urges the slide 212 to the right in Fig. 15. The wheel 176 carries on the back face of its hub flange 186 a stop pin 222 which is spaced from the axis of the wheel 176 a sufficient distance to enable it to meet the flat face of the stop lug 214 when the boss 214 and slide 212 are moved to the full extent of their movement to the right in Fig. 15, but enabling the pin 222 to pass the boss 214 when it lies in the position to the left shown in Fig. 15. The front face of the wheel 176 carries a pin 224 adapted to cooperate with a lug 226 formed on the control lever 180 whereby the wheel 176 when moving counterclockwise into its position of rest may move the control lever 180 also counterclockwise. The shaft 25 projects through the frame plate 6 and carries a disk 228 which carries on its forward face a series of projections or pins 230. The number and the spacing of the pins 230 are chosen in such correlation with the speed of the rotary member 35 that one pin will pass a given point in about the interval desired between strokes of the striking hammer. A hammer arm 232 is secured to a shaft 234 pivoted in the frame plate 6 which carries fixed thereto a short lever 236 and a light tail lever 238 mounted to permit a limited amount of front and back motion of the tail end of the lever 238. A spring member 240 normally urges the lever 238 up in Fig. 11 into engagement with

the pins 230. The top of the lever 238 is formed with a projecting flange 242 which is interrupted by a slot 244 at one portion. A pin 246 is secured in the outer end of the lever 236 and passes through a hole 248 in the lever 238 to prevent rotational movement of the lever 238 on the shaft 234. A bell crank 250 is pivoted at 252 on the frame plate 6 and has a slot 254 formed in one arm to receive a pin 256 secured to the lever 236 for interconnecting the bell crank and the lever 236. The other arm of the bell crank arm 250 carries a pivoted spring pressed pawl 258 having a pin 260 at its nose adapted to engage the teeth of the wheel 176 for stepping the same back to the position of rest. The control lever 180 carries at its lower end a projecting portion 262 having a beveled cam surface 264 adapted to force the lever 238 out of the path of the pins 230 when the control lever 180 lies in the position shown in Fig. 9 and the lever 238 moves upwardly in Fig. 9. The upper end of the cam surface has a notch 266 formed therein adapted to receive the flange 242 when the lever 238 is in its fully raised position, as shown in Fig. 9. The tripping means provided for controlling the operation of the mechanism so far described at the hour includes the arm 134 which is formed with a return portion carrying a pin 268 which acts as a holding latch for the wheel 176. A pawl 270 is pivoted at 272 to the arm 134 and has a pin 274 adapted to limit the counterclockwise rotation of the pawl 270 under the urge of the spring 276. A stop face 278 on the pawl 270 cooperates with the nose 280 on the upper end of the control lever 180 in preventing counterclockwise rotation of the control lever 180 when the arm 134 is in the raised position.

In the operation of the hour striking mechanism, it will be seen that the wheel 176 is normally held in the starting position, as shown in Fig. 9, by the pin 268 on arm 134, the spring 188 being fully wound when the wheel 176 is in this position. The pin 224 on wheel 176 holds the control lever 180 in its normal position, as shown in Fig. 9, in which it is moved to the limit of its motion in a counterclockwise direction against a suitable stop, not shown, and in which the projecting portion 262 at the bottom of the control lever 180 lies in contact with the flange 242 on the lever 238 at the notch 266. When the minute hand next passes through the hour position the long nose 10 on the cam 8 raises the arm 134 sufficiently to permit the pin 268 to clear all of the teeth on the wheel 176, while at the same time the stop face 278 of the pawl 270 moves up into cooperation with the lug 280 at the top of control lever 180. This permits the wheel 176 to rotate clockwise under the urge of the spring 188. The amount of this rotation is limited by the stop pin 222 which is mounted on the rear face of flange 186 as it comes into contact with the flat face of the boss 214 on the stop slide 212, at all times except when the stop slide is cammed to the left in Fig. 15 by cam 218. It will then be seen that the amount of rotation of the wheel 176 is determined by the position of the hour wheel 206 since the position of the boss 214 determines the point at which the stop pin 222 will stop further rotation of the wheel 176. As the lever 134 drops upon completion of the chime cycle 70 the stop face 278 falls from the path of the lug 280 and permits the spring 196 to move the control lever 180 clockwise against a stop, not shown, inasmuch as the pin 224 is now out of the way of the lug 226 due to the initial rotation of the 75

wheel 176. The clockwise movement of the lever 180 moves the projection 262 of the lever off from the flange 242 and opposite the slot 244 so that the lever 238 is now permitted to move inwardly into the path of the pins 230 under the urge of the spring 240. Inasmuch as the rotary member 228 is constantly driven by the synchronous motor the pins 230 will each depress the lever 238 until they pass off from the end of the same, as shown in Fig. 16, with the consequent oscillation of the shaft 234 and hammer lever 232, thus causing the hammer to strike a sounding element 282. At each oscillation of the lever 238 the bell crank 250 is also oscillated simultaneously therewith through the pin 256 and slot 254. This causes the pawl 258 and pin 263 to step the wheel 176 in a counterclockwise direction, one step for each stroke of the hammer. Inasmuch as there are twelve teeth on the wheel 176 it will be seen that the number of strokes will be equal to the numeral of the hour at which the hour hand stands at each operation of the mechanism. At the last stroke of the hammer for any hour as the wheel 176 moves into its position of rest, the pin 224 moves the control lever 180 counterclockwise in Fig. 9. Inasmuch as arm 134 will be raised due to passing over a tooth of wheel 176 at the time, the pivoted pawl 270 will permit the lug 280 to move to the left over the nose of the pawl 270 and when it has passed over the same will return to the position illustrated under the urge of the spring 276. It will also be noted that at the time the control lever 180 moves into its normal position the arm 238 will be at the bottom of its stroke and will not be cammed out of the path of the pins 230 until the arm 238 is released from the pin 230 and is thus raised under the urge of the spring 290. At twelve o'clock the boss 214 would come into the position occupied by the pin 222. At this time, however, the cam 218 moves the slide 212 and boss 214 to the left in Fig. 15, thus removing the boss 214 from the path of the stop pin 222. When the wheel 176 is released at twelve o'clock the rotation of the same is limited, not by the stop pin 222 and boss 214, but by the pin 224, which, after the wheel 176 has made nearly a complete revolution, comes in contact with the opposite face of the lug 226, thus limiting the rotation of the wheel 176 to nearly one revolution. At the time the arm 134 drops, the lever 180 rotates clockwise a small amount, as previously described, and this permits a slight further rotation of the wheel 176, thus allowing for a complete revolution of the wheel 176 at twelve o'clock.

It will be noted that if at any time between striking periods an attempt should be made to manually lift the hammer 232, the flange 242 will engage the bottom face of the notch 266 and prevent sufficient motion of the hammer and related parts to permit engagement of the lever 238 with pins 230. This is to prevent accidental stoppage or other interference with the synchronous motor by lifting the hammer. If desired the hammer lever 232 may be arranged to lift one or more of the chime hammers 108 and the sounding device 282 may then be omitted.

It will thus be seen that applicant has provided a chiming mechanism which can be constructed in the form of an attachment to be used with the standard movement ordinarily used for non-striking or non-chiming clocks and that when an hour striking mechanism, such as that disclosed in applicant's copending application, is used, it is possible for a manufacturer of clocks

to produce one standard type of main clock movement which can be used alone in clocks not having striking or chiming attachments. The striking attachment of applicant's copending application can be used with the same movement for clocks which strike the hour. The chiming attachment of the present invention can be applied to the same standard type movement in conjunction with the striking attachment of the copending application for clocks intended to chime the quarters as well as strike the hours. This avoids the necessity of assembling three different types of main clock movement to correspond with the three types of clocks ordinarily sold. It should also be noted that applicant's mechanism has no parts requiring particularly sensitive adjustment and that the main operating mechanism for the chiming attachment is one integral unit of mechanism. In addition, the means which applicant has disclosed for engaging and disengaging the main chime operating mechanism with the clock motor train requires but very little force to operate, inasmuch as the only member which is moved to connect and disconnect these parts is the very light segment 14 which can be shifted with great ease by the lifting assembly and control lever at all times, even after long periods of usage during which the lubricant in the clock may become gummy or may disappear.

It will be noted that this device provides for maintaining proper operation of the chiming mechanism even after abnormal conditions. The hands may be set forward rapidly and the mechanism will restore the chime to synchronism thereafter by means of the high stop 164 and the long projection 10, as described. If the hands are set backwards, the pawl 18 will permit such motion without actuating the lift lever assembly and thereafter the chime will automatically synchronize itself with the hands in the same manner. The device is also readily adapted to economical quantity production since most of the parts can be made by die stamping or die casting. In this connection it may be noted that the unitary chime operating means may be made as a single die casting including the hammer actuating portion 98, the counting portion 100, 102, 104 and the driving portion 70. When made by die casting it is preferable to plate the device with a hard metal, such as chromium, to reduce the wear on the working surfaces.

While the invention has been described as applied to a combined hour striking and quarter chiming clock, it will be understood that many advantages thereof are to be derived from its use with other types of clocks wherein a load of some character is to be intermittently driven at various times. The use of the terms "chime", "strike", "hammer" etc. in this specification and in the appended claims is illustrative only and therefore comprehensive of such other constructions and is not to be construed in a limiting sense.

I claim:

1. In an electric chiming clock including an electric motor, a time train driven by said motor and a hand arbor driven by said time train, the combination of a rotary stroke determining member, a rotary member continuously driven by the motor, a projection on one of said members movable relative to said one member into and out of the path of the other member, and control means for moving said projection, for causing the rotary member to drive the stroke determining member

by different predetermined amounts at different predetermined times.

2. In an electric chiming clock, the combination of a unitary electric clock movement having a synchronous motor and a time train, an hour striking mechanism comprising a unitary attachment to the movement on the front side thereof and a quarter chiming mechanism comprising a separate unitary attachment to the movement at another side thereof, and means for actuating both attachments from the synchronous motor, said last means including a single shaft constantly driven by the synchronous motor.
3. In an electric chiming clock, the combination of a unitary electric clock movement having a synchronous motor and a time train, an hour striking mechanism comprising a unitary attachment to the movement on one side thereof and a quarter chiming mechanism comprising a separate unitary attachment to the movement on another side thereof, and means for actuating both attachments from the synchronous motor, said last means including a single shaft constantly driven by the synchronous motor.

4. In an electric chiming clock, the combination of an electric motor, a plurality of chime hammers and a unitary rotary chime actuating device comprising a plurality of hammer actuating portions arranged in the general form of a cylinder, a separate counting portion, and a selective driving portion, said portions being secured together to rotate as a single unit. 5

5. A counting device for a chime clock having a rotary hammer actuating member, said counting device including a rotary member movable through more than one revolution for a complete chime cycle, and a series of stops on said member arranged in a path extending for more than one revolution around the member. 10

6. As an article of manufacture, a unitary chime actuating device comprising a plurality of hammer actuating portions arranged in the general form of a cylinder, a separate counting portion, and a selective driving portion all mounted 20 for simultaneous rotation about a single axis and comprising a single die casting. 15

PENNIE R. AYRES.
